[57] CLAIM

The ornamental design for a handset and stand telephone set, substantially as shown and described.

DESCRIPTION

FIG. 1 is a top plan view of a handset and stand telephone set, showing our new design;

FIG. 2 is a front elevational view thereof;

FIG. 3 is a bottom plan view thereof;

FIG. 4 is a rear elevational view thereof;

FIGS. 5 and 6 are respectively right and left side elevational views thereof;

FIG. 7 is a perspective view thereof; and

FIG. 8 is an associated perspective view thereof, showing the entire top surface of the stand, and with the handset inverted and spaced apart from the stand in bracketed relationship.

The cord is shown in fragmentary form, for clarity of illustration and for simplified presentation.

FIG. 1
